UNITED STATES PATENT OFFICE.

JAMES P. COUGHLIN, OF KANSAS CITY, MISSOURI.

LOGGING AND INDICATING DEVICE FOR RADIO TUNING INSTRUMENTS.

Application filed July 10, 1925. Serial No. 42,796.

This invention relates to an improved logging and indicating device for radio tuning instruments and seeks, among other objects, to provide a device of this character which 5 will eliminate the existing necessity of tediously adjusting the tuning instrument or instruments of a receiving set each time it is desired to tune in a particular sending station.

10 The invention seeks, as a further object, to provide a device wherein, after the tuning instrument of a receiving set has been adjusted to tune the set to the wave length of any given sending station, the wave length 15 of the station as well as the call letters of the station may be readily logged upon the chart of the device so that the receiving set may be quickly tuned subsequently to the same station by adjusting the tuning instrument until the finders of the device are 20 brought into position at the log notations of the chart.

Still another object of the invention is to provide a device wherein the finders will be 25 operable in unison with the tuning instrument.

And the invention seeks, as a still further object, to provide a device which may be readily employed in connection with conventional receiving sets and which may be readily attached.

Other objects of the invention not above specially mentioned will appear as the description proceeds.

35 In the accompanying drawings:

Figure 1 is a front elevation showing my improved logging and indicating device in connection with a conventional receiving set.

Figure 2 is a horizontal sectional view on 40 the line 2—2 of Figure 1, looking in the direction indicated by the arrows, and particularly showing the mounting of the pinion of the device.

Figure 3 is a vertical sectional view on the 45 line 3—3 of Figure 1, looking in the direction indicated by the arrows.

Figure 4 is a plan view showing the mounting of the rack member employed.

Figure 5 is a detail cross sectional view 50 particularly showing the mounting of the finders.

Figure 6 is a detail perspective view showing one of the chart cards.

Referring now more particularly to the 55 drawings, I have shown the present inven-

tion in connection with a conventional radio receiving set embodying the usual cabinet 10 to which is fixed a front panel 11 of suitable insulating material. The logging and indicating device is employed in connection 60 with the tuning instrument of the set and I have typically shown such an instrument at 12. An ordinary variable condenser is illustrated but it is to be understood that the present invention is not limited to use 65 with variable condensers but may be employed in connection with radio tuning instruments generally. The condenser is fixed to the panel 11 in any suitable manner and the tuning shaft of the condenser, which 70 shaft carries the usual movable plates, is indicated at 13. As is customary, this shaft is freely accommodated through a suitable openings in the panel and projects at its outer end at the forward side of the panel. 75

Coming now more particularly to the subject of the present invention, I employ an oblong vertically disposed base plate 14 which is positioned flat against the panel 11 at its forward side and is secured at its 80 ends to the panel by bolts or other suitable fastening devices 15. The base plate is preferably of suitable insulating material, and formed in said plate medially thereof, as shown in Figure 4, is a relatively wide longitudinally extending slot 16. The shaft 13 of the condenser 12 projects through this slot at a point midway between the ends thereof and slidably fitting in said slot is a rectangular rack member 17, one of the side 85 bars of which is provided with rack teeth 18. Rising from the end bars of said member are aligned upper and lower lugs 19.

Overlying the base plate 14 is a front plate 20 retaining the rack member 17 in the slot 90 16 of the base plate. The front plate is suitably fixed to the base plate and formed in the front plate medially of said slot is a longitudinally extending slot 21 freely accommodating the lugs 19 of said rack 100 member. At a point midway between the ends of the slot 21, the front plate is, as shown in Figure 1, provided with a circular opening 22, and struck from said plate to extend laterally at opposite sides of the slot are upper parallel flanges 23 and similar lower parallel flanges 24. Slidably fitting between the flanges 23 are removable chart cards 25 and slidably fitting between the flanges 24 are similar removable chart cards 26.

26. These cards may be of any approved material and, in Figure 6, I have shown a typical card in detail.

Fixed to the uppermost of the lugs 19 of the rack member 17 is an oblong loop-shaped finder 27 and fixed to the lowermost of said lugs is a similar finder 28. These finders are provided medially with webs 29 and extending through said webs are screws 30

- 10 screwed into the lugs 19 for rigidly connecting the finders thereto. The finders are of a length to extend transversely from edge to edge of the front plate 20 and are supported by the lugs 19 to closely overlie the
- 15 chart cards 25 and 26. As shown in Figure 1, the left hand chart card 26 is provided at its inner vertical margin with a scale 31 calibrated in terms of degrees, and extending from the web 29 of the lower finder 28
- 20 is a pointer 32 to cooperate with said scale.

Fixed to the outer end of the shaft 13 of the condenser 12 is an insulating knob 33 having a sleeve 34 fitting over the shaft and surrounding said sleeve to coact with the 25 rack teeth 18 of the member 17 is a pinion 35 having a hub sleeve 36 removably fitting over the inner end of the sleeve 34. Extending through both sleeves is a set screw 37 engaging the shaft 13 for rigidly connecting the knob and pinion thereto and, as will be observed, the opening 22 in the front plate 20 is of a diameter to freely receive the pinion so that the pinion may be initially inserted over the outer end of the shaft 30 through said opening to engage the rack teeth 18, when the knob 33 may be applied to the shaft. Preferably, the parts are so assembled that when the movable plates of the condenser 12 are nested between the fixed 35 plates thereof, the finders 27 and 28 stand at the lower ends of the cards 25 and 26.

As will now be seen in view of the foregoing, as the knob 33 is turned in either one direction or the other, for varying the 40 capacity of the condenser 12 and tuning the receiving set to the wave length of a given station, the pointers 27 and 28 will be caused to travel up or down, as the case may be, in front of the chart cards 25 and 45 26. Accordingly, when the set is tuned to the wave length of the station, said wave length may be written upon one of the cards 25 between the side bars of the finder 27, as typically indicated at 38, while the call 50 letters of the station may be written upon one of the cards 26 between the side bars of the finder 28, as typically indicated at 39. As the condenser is operated to tune the set to other sending stations, such stations may, in like manner, be logged upon the cards 25 and 26, as further suggested in Figure 1,

so that the set may be subsequently tuned to any one of said stations, as for instance the station logged at 38 and 39, simply by turning the knob 33 until the pointer 27 is 55 brought to a position over the wave length of said station, when the pointer 28 will, of course, occupy a position over the call letters of the station. I preferably provide a pair of the pointers in order that the wave length 60 as well as the call letters of each station may be logged. Furthermore, it is often found possible to log the call letters of a station and not the wave length thereof, or vice versa, and by providing a pair of the 65 pointers, either the wave length or the call letters of a station may be logged in any such instance. Removable chart cards are employed in order that said cards may be readily renewed should occasion demand, 70 and further, in order that clean cards may be readily substituted for cards which may have become soiled. The scale 31 corresponds to the scale of an ordinary dial as now in common use so that, if desired, 75 readings on the scale, as indicated by the pointer 32, may be logged in a separate log book in accordance with customary practice.

Having thus described the invention, what I claim is:

1. Logging and indicating means for 80 radio receivers, the same comprising a panel mount including a base plate formed with a longitudinal slot, a slide member movable in said slot, a cover plate attached to the base plate and bearing independent groups of indicating means designating wave lengths and stations, respectively, a finder for each group of indicating means connected to the slide member to move therewith, and a rotary tuning element extending through the base and covering plates and 85 geared to the slide member.

2. Logging and indicating means for 90 radio receivers, the same comprising a panel mount including a base plate formed with a longitudinal slot, a slide member movable in said slot and provided at its ends with lugs, a cover plate attached to the base plate and formed with a slot to receive the lugs 95 of the slide member, and provided with independent groups of indicating means designating wave lengths and stations, respectively, a finder for each group of indicating means connected to a lug of the slide member and overlying the cover plate, and a rotary tuning element passing through the slide member and the base and cover plates and 100 geared to said slide member.

In testimony whereof I affix my signature.

JAMES P. COUGHLIN. [L.S.]
